ANGLE COMPUTER

Chester Sig Anderson, St. Charles, Ill.

Application August 9, 1951, Serial No. 241,008

2 Claims. (Cl. 33—207)

1

The present invention relates to a plumbing device and more particularly to a novel angle computer for locating, aligning and positioning sheets of wallpaper, metal plates, pipes or other members or parts in a vertical or in a horizontal plane, or arranging and disposing them in any desired angular position or alignment.

One of the important objects of the present invention is the provision of a novel device for plumbing sheets of wallpaper to assure that successive sheets thereof are hung in parallel and aligned vertical planes whereby to secure proper pattern design and abutting relation between adjacent sheets.

Another important object is the provision of a novel angle computer which may be arranged for alignment with a vertical or horizontal plane, or may be readily and easily adjusted and arranged for accurately determining and positioning a member at a predetermined or desired angle with respect to the vertical or horizontal planes. When adjusted to the vertical, horizontal or desired angle, the device may be quickly and easily attached to the member to be positioned, whether it be a sheet of paper or fabric, a section of wood or metal, or a section of pipe to arrange said member in the desired plane or at an angle to the desired vertical or horizontal plane. For example, in locating a steam pipe or a drain pipe, it is important to mount the pipe at a predetermined angle to allow for a desired drop or fall to assure proper passage or drainage of the liquid.

The present invention further comprehends the provision of a novel means for computing angularity and for assuring uniformity in angular alignment whereby the operator can quickly secure or match any angle and continually duplicate the alignment or angle desired. Among such uses is the lining up of refrigerator coils, the securing of a desired angle in sheet metal work or in welding.

Another object of the present invention is the provision of a novel angle computer having a spirit level and a dial computed through 360°, and a novel means and manner of assembly thereof to assure optimum accuracy and to allow for ready adjustment to any desired angular relation.

A further object of the present invention is the provision of a novel means and manner of applying and retaining the novel angle computer upon a sheet or object whose angle is to be determined.

Further objects are to provide a construction of maximum simplicity, efficiency, economy and ease of assembly and operation, and such further objects, advantages and capabilities as will later more fully appear and are inherently possessed thereby.

In the drawings:

Figure 1 is a view in front elevation of the novel angle computer.

Fig. 2 is a top plan view of the angle computer of Fig. 1.

Fig. 3 is a fragmentary view of a corner of a room and showing the paper hanger employing the novel angle computer for vertically locating

2

a sheet of wallpaper at the corner to thereby assure hanging this sheet on a side wall in its plumbed or vertical position.

Fig. 4 is a view in vertical cross section through the novel angle computer mounted on a sheet for plumbing or aligning that sheet.

Fig. 5 is a view in horizontal cross section taken in a plane represented by the line 5—5 of Fig. 1.

10 Fig. 6 is a view in perspective of a workman applying the novel angle computer to an upright section of pipe to accurately locate this section in its proper angular position.

Fig. 7 is a fragmentary diagrammatic view 15 showing the successive steps or stages of adjusting the dial and spirit level of the angle computer to the assembled relation of Fig. 1.

Fig. 8 is a fragmentary view in front elevation of the present angle computer in which the level 20 has been rotated through an angle of 90° from the position of Fig. 1, whereby the device may be used in a horizontal plane or secure horizontal alignment.

Fig. 9 is a fragmentary top plan view similar 25 to Fig. 2 but showing the computer anchored onto an upright edge or rail of a door or other section.

Referring more particularly to the disclosure in the drawings and to the novel embodiment 30 therein shown for illustrating the present invention, the novel angle computer comprises a frame including a rear plate 10 and a face plate 11 preferably constructed of a rigid material such as metal or the like having the desired inherent strength and rigidity. These plates or front and 35 rear members 10 and 11 are spring-biased toward closed position and abutting relation by a spring clip or clamp member designated generally by the numeral 12.

40 This spring clip or clamp member includes a pair of manually-actuated clamping jaws 13 and 14 each affixed to or formed integral with the inner end of its respective plates 10 and 11, and each clamping jaw provided with an outwardly 45 projecting finger-engaging piece 15 extending through a slot 16 in an arcuate or substantially U-shaped spring 17 which spring-biases the jaws and their plates to clamping position (Figs. 2, 4 and 5). These members 15 diverge in such manner that the operator upon grasping them between the thumb and forefinger and applying pressure thereto causes the spring-biased plates 10 and 11 to separate. An opening 18 in each finger piece 15 permits the angle computer to be hung up when not in use.

55 Mounted upon the outer or face plate 11 is a dial 19 in the form of a disc divided into angles from 0 to 90° in each quarter or segment of the dial. This dial is mounted on a center screw 20 and retained by a wing nut 21 and provided adjacent its forward edge or periphery with an elongated slot 22 adapted to receive therein the shank of screw 23. A wing nut 24 is adapted to lock the screw 19 and dial 19 in its proper, adjusted 60 or aligned position. This elongated or arcuate

65

slot 22 extends for approximately 20°, i. e. 10° laterally from the marking 90° to substantially the markings 10° and 80° (see Fig. 7).

Rotatably mounted on the center screw 20 is a housing or support 25 mounting a spirit level 26 in its upper portion and provided with oppositely disposed indicating pointers 27 adapted to be adjusted to any desired angle with respect to the markings on the dial upon loosening of the wing nut 21.

The front plate 11 is provided with suitably spaced indentations or dimples 28 projecting beyond the rear surface of the front or face plate, and with a pair of spaced aligning tongues or projections 29 preferably stamped out of the metal of this face plate (see Figs. 1, 2, 4 and 5). The indentations or dimples 28 as well as the rearwardly projecting heads of the screws 20 and 23 are adapted to augment the holding power or gripping action of the plates 10 and 11, particularly if the sheet, plate or member upon which the device is to be mounted and whose angle is to be computed is of a non-rigid material. The rear plate 10 is provided with openings or recesses 30 for receiving the head of the screws 20 and 23, and openings or recesses 31 for receiving the spaced, rearwardly projecting aligning tongues or projections 29.

Figs. 3 and 4 show the present device employed in hanging wallpaper in which the device is clamped to the edge 32 of the wallpaper 33 with the edge 32 of the paper abutting the tongues or projections 29 projecting rearwardly from the face plate 11. By viewing the spirit level 26 which determines whether the paper is plumb or vertically disposed, the paper hanger swings the paper to the right or left in a manner similar to a pendulum until the bubble in the spirit level appears at the center. When this occurs the paper hanger knows that the edge 32 of the wallpaper 33 is vertically disposed and he thereupon pastes or affixes the upper end of the paper to the wall and smooths the paper downwardly. Then upon removing the present device by pressing upon the spring fingers 15, he opens the jaws of the clamp and removes the device laterally to permit the remainder of the sheet to be pasted to the wall.

The forward or outer end 34 and the similar end 35 of the plates 10 and 11, respectively, are formed to provide elongated, complementary and substantially V-shaped grooves for facilitating anchoring the device onto an upright section of pipe 36 as shown in Fig. 6 of the drawing, or onto the edge of a door rail or other member 37 as shown in Fig. 9. In the position shown in Figs. 6 and 9, the spirit level is mounted as in Fig. 1 if the pipe section 36 or door rail 37 are to be vertically disposed.

If the pipe section 36 is to be positioned at an angle with respect to the vertical, the spirit level 26 is adjusted so that its pointers or indicators 27 are adjusted to the desired angle marking on the dial 19. Then when the pipe section 36 is disposed at the proper angle, the bubble of the spirit level 26 will be centered. If the pipe section 36 is to be horizontally arranged, the level 26 is adjusted to the position shown in Fig. 8, or if the pipe section 36 is to be inclined as for proper drainage, the level is adjusted to the proper angle.

Fig. 7 discloses the means and manner of initially locating and adjusting the spirit level and dial of the angle computer. This is preferably accomplished by clamping the device to a known

vertical as shown at (1). This master aligning edge may be a sheet or metal plate and may have its accurately aligned, vertical edge abutting against the aligning tongues or projections 29.

5 The spirit level 26 is then adjusted as shown at (2) until its bubble is centrally disposed and the thumb or wing nut 21 is tightened to lock the level in adjusted position. Then the dial 19 is rotated as shown at (3) to bring the 90° or 0° markings thereon aligned with the ends of the oppositely disposed indicators or pointers 27 on the spirit level 26, whereupon the wing nut 24 is tightened to lock or retain the dial in this adjusted position as in Fig. 1.

15 However, after the spirit level 26 and the dial 19 have been initially adjusted as above noted, the level 26 may be subsequently adjusted to any other angular position. In Fig. 8 the level has been rotated through an arc of 90° from the 20 position of Fig. 1 for securing horizontal rather than vertical alignment, but it will be readily appreciated that the level 26 may be positioned to secure any desired angular position with respect to the dial 19, and when the angle computer or device is clamped onto a flat plane, sheet, pipe or other member, that member may be disposed at any desired angle. If desired, the plates 10 and 11 may be formed with a strengthening or ornamental bead 38, as shown.

30 Having thus disclosed the invention, I claim:

1. A device adapted to plumb and align sheets of wallpaper being applied to a side wall, comprising a pair of separable plates adapted to clamp therebetween an edge of the wallpaper, 35 aligning means carried on one plate and projecting through openings in the other plate for locating the edge of the wallpaper with respect to said plates, a dial adjustably mounted on the face of one of said plates divided into angle 40 designations throughout its circumference, and a spirit level adjustably mounted on said dial and having indicating means adapted to be aligned with selected angle designations on said dial.

45 2. An angle computer adapted to be detachably mounted upon a sheet of wallpaper, metal plate, pipe section or other member for positioning the same in a vertical or horizontal plane or at an angle with respect thereto, comprising

50 a backing plate and a face plate having spring-actuated clamping jaws for spring-biasing said plates toward contacting engagement but permitting separation of the plates to anchor the angle computer onto the member being positioned, aligning projections on one of said plates 55 and projecting through openings in the other plate, a dial adjustably mounted on the face of one of said plates divided into angle designations, and a spirit level adjustably mounted on

60 said dial and having indicating means adapted to be aligned with selected angle designations on said dial.
